DESIGN FOR AN OCCUPANT PROPELLED SURFBOARD

Bert Lee, Hollywood, Calif., assignor to H. E. Barke, Oakland, Calif.

Application June 26, 1944, Serial No. 114,195

Term of patent 7 years

(Cl. D71—1)

To all whom it may concern:

Be it known that I, Bert Lee, a citizen of the United States, residing at Hollywood, in the county of Los Angeles and State of California, have invented a new, original, and ornamental Design for an Occupant Propelled Surf Board, of which the following is a specification, reference being had to the accompanying drawing, forming a part thereof, in which:

Figure 1 is a top plan view of the occupant propelled surf board showing my new design,

Figure 2 is a side elevational view of the same; and

Figure 3 is a transverse section on the line 3—3 of Figure 1.

I claim:

The ornamental design for an occupant propelled surfboard, as shown.

BERT LEE.
